UNITED STATES PATENT OFFICE.

EDWARD A. RUSSELL, OF CHICAGO, AND PAUL B. PARKS, OF OAK PARK, ILLINOIS, AS
SIGNORS TO VAPOR CAR HEATING COMPANY, INC., OF CHICAGO, ILLINOIS, A COR-
PORATION OF NEW YORK.

FLOAT TRAP.

Original application filed July 28, 1923, Serial No. 654,452. Divided and this application filed April 9,
1925. Serial No. 21,810.

To all whom it may concern:

Be it known that we, EDWARD A. RUSSELL and PAUL B. PARKS, citizens of the United States, residing at Chicago, Illinois, and 5
5 Oak Park, Illinois, respectively, have invented certain new and useful Improvements in Float Traps, of which the following is a specification.

This invention relates to a float trap de-
10 signed to permit the discharge of water or
other liquid therethrough while maintain-
ing a liquid seal against the escape of vapor,
such as steam. The device is particularly
designed for use in connection with a car
15 heating system of the general construction
shown in the patent to E. A. Russell, No.
1,440,701, granted January 2, 1923. The
present application is a division of our prior
application, Serial 654,452, filed July 28,
20 1923.

In the car heating system disclosed in the
Russell patent referred to above, circulation
through the radiating coil is controlled by
a valve device having a centrally arranged
25 revoluble valve body and constructed so that
in one position of the valve body steam is ad-
mitted to the inlet end of the radiating coil
and water of condensation withdrawn from
the coil at the return end thereof and also
30 at a point intermediate the ends of the coil,
while in another position of the valve body
the inlet and outlet ends of the coil are
closed and steam is short-circuited from the
low pressure side of the vapor regulator, di-
35 rectly to the thermostat chamber of said
regulator. In order to provide for dis-
charging the water of condensation re-
ceived in the chamber to which the interme-
diate water outlet from the coil is connected,
40 this chamber (in the patented valve) is in
communication with the chamber connected
with the thermostat casing of the vapor
regulator through a duct in the bottom of
the valve casing arranged so as to be at all
45 times water-sealed against the passage
therethrough of steam at the low pressures
that the valve is designed to handle.

This arrangement may be objectionable
under some conditions, because of the dan-
50 ger of the water freezing in the duct and
more particularly because of the likelihood

of the duct becoming clogged by dirt or
other foreign matter.

According to the present improvement, as
first disclosed in our prior application Se- 55
rial 654,452, the construction of the valve is
modified by connecting the chamber receiv-
ing water through the water outlet of the
coil directly with the drip port chamber
through which water is discharged when the 60
valve is in position to shut off inflow of
steam to the radiator, these two chambers in
the improved valve, constituting in fact a
single chamber, and by providing a float
valve of improved construction which will 65
allow the escape of water from the drip port
chamber while preventing outflow of steam.

This improved valve, or float trap, forms
the particular subject-matter of the present
application. This valve is simple in con- 70
struction and entirely automatic in opera-
tion, and will permit the free discharge
therethrough of water at all times, only
enough water being trapped within the valve
casing to effectively seal the trap against the 75
escape of steam. The lower portions of the
valve, and of the valve casing, have inter-
fitting conical formations, whereby if the
small body of water trapped therebetween
should freeze, it will merely raise the valve 80
and not crush it. While this float trap is
particularly useful in a car-heating system
such as briefly described above, it is equally
adapted for use wherever the discharge of a
liquid from any sealed vapor-containing sys- 85
tem is desired.

Additional objects and advantages of this
improved device will be apparent from the
following detailed description of the im- 90
proved float trap in connection with a por-
tion of a car heating system such as referred
to hereinabove.

In the accompanying drawing:

Fig. 1 is a central vertical section through
the float trap and the control valve of the 95
car heating system, with which valve the
float trap is connected.

Fig. 2 is a horizontal section through the
control valve, taken substantially on the line
2-2 of Fig. 1. 100

Fig. 3 is a central vertical section through
the float trap taken on a plane at approxi-

mately 45° to the plane of Fig. 1. The plane of Fig. 3 is substantially indicated by the line 3—3 on Fig. 4.

Fig. 4 is a horizontal section on an enlarged scale, taken substantially on the line 4—4 of Fig. 1, and looking in the direction of the arrows.

The control valve for the car heating system comprises a casing 10 having a central 10 circular space 11 in which is arranged a revoluble valve body 12 consisting of an upper disk 13, a lower disk 14 and vertical webs 15 and 16. The valve body is provided with a stem 17 by means of which the valve is rotated from above by means of mechanism not here shown. The space within the casing 10 around the valve body is divided by webs into chambers *a*, *b*, *c*, *d*, and *e*, each of 15 which opens into the central space 11 in which the valve body is located.

Steam flows from the train supply pipe through the vapor regulator, and then through pipe 19 to chamber *a*. Pipe 20 leads from chamber *b* to the car heating radiator. 25 A pipe 21 leads from a point intermediate the ends of the radiator coil to chamber *c*. The return end of the radiator discharges through pipe 22 into chamber *d*. A pipe 23 leads from chamber *e* to the thermostat casing 30 of the vapor regulator.

It will be observed that the apparatus operates like the ordinary vapor car heating system except that while the radiator is receiving steam, water of condensation may 35 be discharged therefrom, not only at the return end of the coil, but also at a point intermediate the inlet and return ends thereof. With the parts of the apparatus in the positions shown in the drawings, steam 40 passes through pipe 19 into chamber *a*, then through space 11 to chamber *b*, and through inlet pipe 20 to the radiator coil. After traversing the first section of the coil, water of condensation is discharged through pipe 45 21 into valve chamber *c*, the steam passing on through the second section of the radiator coil. The medium (either water, steam or a mixture of water and steam) discharged from the return end of the coil through pipe 50 22 into chamber *d*, passes into chamber *e* and thence through pipe 23 to the thermostat chamber of the vapor regulator. The condition of the medium discharged to the thermostat governs the operation of the 55 pressure reducing valve of the regulator.

When the valve body 12 is shifted from the full line position as shown in Fig. 2, to the dotted line position, steam entering chamber *a* passes directly into chamber *e* 60 and then to the thermostat chamber of the regulator. The radiator is thus short circuited and the steam therein when condensed flows through pipes 20, 21 and 22 into chambers *b*, *c* and *d*, respectively, which chambers are now in communication with each

other. The water received by chamber *c* while the radiator is supplied with steam, and the water which passes into the valve chambers *b*, *c* and *d* when steam is cut off from the radiator, flows out from chamber *c* 70 through a discharge duct 28 in the bottom wall 29 of the valve casing, this duct leading to a drip pipe 30 screwed into a boss 31 on the under side of the valve casing.

When steam is shut off from the radiator, 75 there is no objection to having the water outlet from chamber *c* open to the atmosphere, but inasmuch as this chamber also provides for discharge of water of condensation from an intermediate point in the 80 coil while the system is under steam, it is necessary to provide some means for preventing the escape of steam from the valve at this point while permitting the outflow of water. This is accomplished by providing the drip pipe 30 with a float valve 32 which is arranged in a float chamber casing secured to the end of the drip pipe. The float valve consists of a hollow sheet metal structure, the middle portion of which is 85 cylindrical while the upper and lower ends 33 and 34 are conical. The float valve casing is composed of an upper casing section 35 and a lower casing section 36 which latter may have an internally threaded boss 37 90 for an outlet pipe 38. The upper section 35 of the casing is provided with an externally threaded boss 39 for attachment to drip pipe 30 by means of the union 40. The upper wall 41 of casing section 35 is formed on 95 its under surface with radial grooves 42 providing segmental pads 43 against which the upper end of the valve bears when the valve is raised. Lugs 44 are provided for 100 guiding the upper end of the valve. When the valve is raised water may flow down into the valve chamber within the casing through the grooves 42, and between the lugs 44. The lower member 36 of the float valve casing is formed with a conical bottom 45 having a central opening 46 therein, around 105 which is formed a raised valve seat 47. Member 36 is provided with a vertically extending cylindrical guide flange 48 to guide the lower end of the valve. This 110 flange is recessed, that is, diminished in height at intervals, as indicated at 49, to points below the cylindrical portion of the valve, so as to allow water to flow into the 115 space between the under surface of the valve and the conical bottom of the casing. 120

The valve 32 is normally seated by gravity and by any pressure of steam that there may be above it, which, however, is slight in a vapor system of the type described, and when water is discharged from chamber *c* in sufficient quantity to float the valve 32, port 46 will be opened to allow the discharge of water through outlet pipe 38. Only a 125 small amount of water is trapped under the 130

valve, in the narrow space between the interfitting conical portions 34 and 45 of the valve and valve casing, and in case this water should freeze, its expansion will merely 5 raise the valve and not crush it.

While this float trap is particularly useful in connection with the control valve for the vapor car heating system, as above described, it is obvious that it may function 10 in a like manner in any other system where it is desired to discharge liquid from a vapor-containing system without permitting the escape of vapor through the liquid discharge pipe. All of such uses of the float 15 trap are contemplated, and intended to be covered by the following claims.

We claim:

1. A float valve device comprising a valve 20 chamber having an inlet opening in the top and a discharge opening in the bottom, the top and bottom being conical, and the under surface of the top formed with substantially

radial grooves, and a float valve having conical ends in said chamber, and guide lugs 25 projecting into the chamber for guiding the valve without interfering with the flow of fluid therearound.

2. A float valve device comprising a valve chamber having an inlet opening in the top and a discharge opening in the bottom, the 30 top and bottom being conical, and the under surface of the top formed with substantially radial grooves, a float valve having a cylindrical central portion and conical upper and lower ends, the conical lower end when the 35 valve is in lowered position sealing the discharge opening, and guide means projecting into the casing for guiding the cylindrical portion of the valve and centering the conical ends thereof within the conical portions of the casing without interfering with the flow of fluid around the valve. 40

EDWARD A. RUSSELL.

PAUL B. PARKS.
